GAME DEVICE

Lambert W. Abell, Los Angeles, Calif.

Application February 17, 1937, Serial No. 126,234

2 Claims. (Cl. 273—138)

This invention relates to games of the type in which skillful manipulation is necessary to control the course of a moving object in order to direct the latter to a predetermined location having a certain value in the playing of the game.

An object of the invention is to provide a game device including a body of transparent liquid in which a playing piece such as a coin or other object can be deposited, and the course of the coin through the liquid under the action of gravity controlled by manipulation of the liquid container in order to direct the coin to a predetermined location or goal in the container.

Another object of the invention is to provide a game device of the above described character wherein the liquid in the container is viscous so as to very appreciably retard the movement of the coin under the action of gravity, to therefore establish a time interval of "play" during which the downward course of the coin in the liquid can be controlled by tilting and other manipulations of the container requiring skill to direct the coin, during the time available, to a balanced position on a peg or other support in the body of liquid, or to some predetermined location having a certain meaning or value, or at which some action will be effected or indicated.

With these and other objects in view, the invention consists in the combinations and arrangements of elements as set forth in the following specification, and particularly pointed out in the appended claims.

In the accompanying drawing,

Figure 1 is a view showing in vertical longitudinal section, one form of game device embodying this invention;

Figure 2 is a plan view of the game device;

Figure 3 is a fragmentary detail sectional view taken on the line 3—3 of Figure 1.

Referring specifically to the drawing, the invention in its illustrated embodiment comprises a container C preferably constructed of glass or other transparent durable material and composed of a base portion 10 from which rises a cylindrical tubular portion 11, the upper open end of which is provided with a closure structure including a removable cap 12 and a ring 13 permanently secured to the portion 11. The cap 12 is provided with a conventional form of cylinder lock 14, having an arm 15 at the inner end of its rotary barrel 16 which, in the locked position of the barrel, is adapted to co-act with the horizontal portion of an L-shaped slot 17 in the ring, to lock the cap thereon.

The base portion 10 has the general shape of

a bowl so as to provide a curved side 18 and a flat bottom 19, which latter is adapted to rest on a horizontal support such as a table to support the container with its tubular portion 11 in a perpendicular position.

The container is adapted to be filled to within a short distance of its top, with a transparent, viscous liquid L, such as syrup or oil, for example; and the cap 12 is provided with a slot 20 for the passage of a playing piece such as a coin or other similar object. Permanently fixed by cement 21 or other means to the bottom 19 within the base portion 10 is a support in the form of a peg 22 which is preferably co-axially arranged with respect to the cylindrical tubular portion 11 and projects into the lower end of the latter.

The portion 11 provides a column of viscous liquid, the viscosity of which is such as to very appreciably retard the downward movement in the liquid of a playing piece, such as a coin of small denomination, deposited in the slot 20, it being found in practice that the viscosity of the liquid should be sufficient for a time interval of approximately twenty-five to thirty seconds to elapse between the deposit of the coin and the travel thereof to a point at the level of the top of the peg, in order for a player to have a fair opportunity to exercise his skill and judgment in controlling the downward course of the coin.

In the use of the invention, the object is to control the course of a deposited coin by so tilting and otherwise manipulating the container, as to direct the coin to a substantially central position on the peg 22 so that as a result of the central support provided by the peg, and the surrounding support provided by the viscous liquid, the coin will be balanced on the peg and will remain thereon so long as the container is undisturbed on a substantially horizontal support.

In manipulating the container, it can be lifted bodily or can be conveniently rocked or rolled about on the curved side 18 of its base portion 10. The skill of a player can be tested to a greater degree by attempting to direct one or more additional coins onto the first coin supported by the peg 22, this maneuver becoming increasingly difficult as the number of coins which a player succeeds in stacking on the peg increases. To a limited extent, the viscosity of the liquid aids in retaining a coin on the peg when the container is being tilted in controlling the movement of a subsequently deposited coin, and thus renders it possible by skillful maneuvering, to place coins in a stack on the peg.

Furthermore, in slowly gravitating through

the viscous liquid, a coin is subjected to a minimum amount of feathering from the approximately level position it occupies when leaving the surface of the liquid, so that the efforts of a player to control the coin are mainly directed to maintaining the coin centrally above the peg. It is, of course, necessary for the player to observe the coin from different viewpoints at approximately right angles to each other in order to center the coin with respect to the peg, and it will be appreciated that as such observations must be made as the container is being manipulated that considerable skill is required to balance a coin on the peg.

15 When it is desired to empty the container of coins, the cap 12 is unlocked and removed, and the liquid L poured from the container into a suitable vessel through a sieve which serves to separate the coins from the liquid, after which

the liquid can be poured back into the container and the cap replaced.

What is claimed is:

1. A game device comprising a container having a base portion and a transparent tubular portion rising therefrom; a body of liquid providing a liquid column in said tubular portion; said tubular portion having an opening for the deposit of a playing piece into the liquid; and a vertical peg in the liquid to which a player endeavors to direct the playing piece by manipulation of the container. 5

10 2. A game device comprising manipulative means defining a transparent columnar enclosure having a top opening through which a playing piece can be deposited; a body of liquid in the enclosure; and a peg in the liquid at a location remotely below the surface of the liquid. 15
